UNITED STATES PATENT OFFICE.

ROBERT D. LOOSE, OF FORT WORTH, TEXAS.

SPARK-PLUG FOR INTERNAL-COMBUSTION ENGINES.

1,191,603.

Specification of Letters Patent.

Patented July 18, 1916.

Application filed January 18, 1915. Serial No. 2,953.

To all whom it may concern:

Be it known that I, ROBERT D. LOOSE, a citizen of the United States, and a resident of the city of Fort Worth, in the county of 5 Tarrant and State of Texas, have invented a certain new and useful Improvement in Spark-Plugs for Internal-Combustion Engines; and I do hereby declare that the following description of my said invention, 10 taken in connection with the accompanying sheet of drawings, forms a full, clear, and exact specification, which will enable others skilled in the art to which it appertains to make and use the same.

15 My invention relates to improvements in electric ignition devices, and primarily to spark plugs utilized as a part of the modern electrical system of an internal combustion or gasoline motor.

20 The object of my invention is the production of a spark-plug having insulated and non-insulated electrodes within the cylinder or cylinders of an engine of the class described, between which electrodes there 25 is a varying degree of separation, so that an induced electrical spark, irrespective of magnitude, will traverse the space or gap between said electrodes at some point of their length. This and other objects and 30 advantages I accomplish by the means hereinafter fully described and as particularly pointed out in the claims.

In the drawings which serve to illustrate my said invention more fully, Figure 1 is a 35 side elevation of a spark plug constructed in accordance with my invention. Fig. 2 is a fragmental side view of a spark plug provided with a single pair of my improved electrodes. Fig. 3 is an inner end view of the 40 form shown in Fig. 2. Fig. 4 is a view similar to Fig. 2 illustrating a somewhat differently shaped grounded electrode. Fig. 5 is an inner end view of the form shown in Fig. 4. Fig. 6 is an inner end view of 45 a spark plug provided with three equi-distant grounded electrodes. Fig. 7 is an inner end view of a spark plug provided with four equi-distant grounded electrodes. Fig. 8 is a view similar to Fig. 7, showing but two 50 grounded electrodes.

Like parts are indicated by corresponding characters or symbols of reference in all the figures of the drawings.

In Fig. 1, I illustrate a conventional type 55 of spark plug having a hollow metal bushing 1 threaded on its lower or inner end por-

tion 2 for engagement in corresponding screw threads in the opening in the motor cylinder and provided with a hexagonal or similarly shaped head 3, adapted to be 60 gripped by a turning wrench, an insulator 4 of porcelain, mica or other suitable material, a threaded gland 5 for suitably clamping the insulator within the bushing, a spindle 6 extending centrally longitudinally through 65 the bushing and having its outer projecting end provided with a terminal 7 to which a high tension electric wire can be connected by a terminal thumb nut 18 on said projecting end. The inner end 8 of the spindle projects considerably beyond the inner end of 70 the bushing of the spark plug and forms the insulated electrode of the device.

It is, however, to the grounded or non-insulated electrode or electrodes attached to 75 and projecting from the bushing 1, to which my invention is particularly directed, and in one of the exemplifications thereof: viz, Fig. 1, one of the said non-insulated or grounded electrodes consists of a depending, inwardly 80 curved member 9, having its upper end affixed to the lower face of the bushing and its lower end rebent to produce a reentrant member 10, which member extends upwardly but divergently from the insulated electrode 8. Located preferably on the opposite side of electrode 8 and likewise non-insulated and attached to the lower face 85 of the bushing 1, I provide an electrode 11 comprising a depending member 11^a, possessed of a horizontal portion 12, extending inwardly and closely to the electrode 8, which portion 12 is then downwardly bent and divergently spread relative to said electrode 8, forming a diverging member 13, 90 95 Fig. 1.

It is now to be observed that the members 13 and 10 of the electrodes 11 and 9, respectively, are arranged in parallelism to each other and likewise in the same vertical plane 100 as the electrode 8, Fig. 8, yet the lower portion of the member 10 and the upper end of member 13, respectively, are located nearest the said electrode 8, whereby in the case of a spark induced by a weak source of electrical energy, the said spark will bridge the nearest distances, between the electrodes 8, 9, and 11, respectively, at the lower end of members 8 and 10 and medially of 8 and the upper portion of 13, producing two sparks 110 as it were, and thereby increasing the efficiency of the spark plug; and, it is to be

observed that as the source of electrical energy becomes higher powered, as for instance in the speeding up of a magneto due to the operation of the motor already referred to, the induced sparks will increase in strength, and breadth until the members 13, 8, and 10 may be substantially enveloped thereby.

I now desire it understood that I do not confine myself to one pair of oppositely disposed electrodes 9 and 11, as for instance, in Figs. 6 and 7, I illustrate a plurality thereof disposed concentrically about the insulated electrode 8.

In Figs. 2, 3, 4, and 5, I show electrodes of various shapes in cross section, any of which may be employed without change or modification.

While herein I have disclosed the preferred mode of practising my invention, I may make such changes and alterations therein as may occur to one skilled in the art, or permitted under the doctrine of equivalents.

Having thus fully described my invention I claim as new and desire to secure to myself by Letters Patent of the United States:—

1. An article of the class described including a body and a member insulated therefrom, passing through said body and therebeyond, a member non-insulated and depending from said body, and divergently arranged with respect to said insulated member, and another member non-insulated and likewise depending from said body and convergently arranged with respect to said insulated member.

2. An article of the class described including a body and a member insulated therefrom, passing through said body and therebeyond, a member non-insulated and depending from said body, and divergently arranged with respect to said insulated member, and another member non-insulated and likewise depending from said body and convergently arranged with respect to said insulated member, said non-insulated members being disposed in parallelism to each other.

3. An article of the class described including a body and a member insulated therefrom, passing through said body and therebeyond, a member non-insulated and depending from said body, and divergently arranged with respect to said insulated member, and another member non-insulated and likewise depending from said body and convergently arranged with respect to said insulated member, said non-insulated members being disposed in parallelism to each other, and in adjacency to said insulated member.

4. An article of the class described including a body and a member insulated therefrom and passing through said body and therebbelow, a pair of depending members non-insulated from and depending from said body, both adjacent said insulated member; one convergently thereto and one divergently therefrom.

5. A spark plug including a body, an electrode extending axially through and beyond said body, said electrode being insulated from said body, an electrode depending from said body, near the margin thereof, and non-insulated therefrom, said last named electrode extending radially toward said axial electrode to close adjacency therewith and terminating in a sharp corner, and an extension of said electrode extending divergently from said axial electrode, thereby producing a spark gap of gradually increasing length between said electrodes.

6. A spark plug including a body, an electrode extending axially through and beyond said body, said electrode being insulated from said body, a second electrode depending from said body, near the margin thereof, and non-insulated therefrom, said second electrode extending radially toward said axial electrode to close adjacency therewith and terminating in a sharp corner, and an integral extension of said second electrode extending from said electrode at said corner downwardly and divergently from said axial electrode, thereby producing a spark gap of gradually increasing length between said electrodes, all of said electrodes being located in the same plane.

7. A spark plug including a body, an electrode extending axially through an exteriorly of said body, said electrode being insulated from said body, a second electrode depending from said body, near the margin thereof, and non-insulated therefrom, said second electrode extending radially toward said axial electrode, intermediate the length of the exterior portion thereof, and to close adjacency therewith, and terminating in a sharp corner, and an integral extension of said second electrode extending from said electrode at said corner and extending downwardly and divergently from said axial electrode, thereby producing a spark gap of gradually increasing width between said electrodes, all of said electrodes being located in the same plane.

In testimony whereof I have hereunto set my hand in the presence of two subscribing witnesses.

ROBERT D. LOOSE.
